PORTABLE HANGER FOR LADY'S PURSE

Jane M. Czarny, 5919 Larkins, Detroit, Mich. 48210

Filed Aug. 30, 1972, Ser. No. 284,747

Term of patent 14 years

Int. Cl. D3—99

U.S. Cl. D87—2 R

FIG. 1

FIG. 6

FIG. 2

FIG. 4

FIG. 3

FIG. 5

FIG. 1 is a perspective view of a portable hanger for a lady's purse showing my new design, the fragmentary dash line showing of a support and purse is for purposes of illustration only;

FIG. 2 is an enlarged top plan view of the portable hanger;

FIG. 3 is a side elevational view thereof;

FIG. 4 is a front elevational view;

FIG. 5 is a rear elevational view; and

FIG. 6 is a cross sectional view on the line 6—6 of FIG. 2.

The broken line fragmentary showing of a lateral support and purse in FIG. 1, is for illustrative purposes only.

I claim:

The ornamental design for a portable hanger for lady's purse, as shown and described.
